UNITED STATES PATENT OFFICE

FRANK H. WAITE AND GEORGE W. DAVEY, OF LONG ISLAND CITY, NEW YORK

GAS PRODUCER

Application filed February 18, 1925. Serial No. 10,109.

This invention relates to gas producers, more particularly to a novel and improved wall or lining therefor which may be maintained at a temperature considerably below the temperature within the producer and thus prolong the life of the construction.

Various means have been resorted to in gas producer construction to keep the inner wall at a temperature below the fusing point and prevent clinker formation on the inner wall of the producer. In some instances water jackets have been built around the producer lining and in other instances, fine jets of air have been blown through the wall adjacent to the fuel bed so as to prevent clinker formation and at the same time keep the temperature of the wall below the fusing point. Neither of the above means have proven satisfactory because either the entire producer lining must be replaced when it breaks down or the producer linings crack because of the uneven temperature maintained throughout its surface. As the result of long practice and experience in producer construction, we have found that the most practical manner of maintaining the producer lining at a temperature below the fusing point and maintaining a comparatively even temperature of the lining throughout its entire surface, is by means of introducing air in all directions through the interior of the producer lining and at the same time utilizing the air which becomes preheated for aiding combustion.

A further object of our invention is to provide a gas producer lining which is built up of superimposed blocks constructed and arranged to provide continuous air passages or channels throughout the entire surface of the wall when so constructed, so that a constant flow of air or a mixture of air and steam may take place through the gas producer lining and particularly the blocks so that they are maintained at a temperature below the fusing point.

In order to more fully understand and appreciate our invention, reference is had to the accompanying drawings, showing a preferred embodiment thereof, wherein;

50 Figure 1 is a vertical sectional view

through a gas producer constructed in accordance with our invention.

Figure 2 is a sectional view therethrough, on the line 2—2 thereof.

Figure 3 is a bottom view of an outer block. 65

Figure 4 is a face view of the outer block.

Figure 5 is an end view thereof.

Figure 6 is a perspective view of the block.

Figure 7 is a top view of the inner block.

Figure 8 is a face view thereof. 60

Figure 9 is an end view.

Figure 10 is a perspective view of the inner block.

Figure 11 is a horizontal sectional view taken through a producer built up of and 65 utilizing the inner block shown in Figures 7 to 10 inclusive.

Referring now to the drawings, wherein like reference characters designate corresponding parts throughout the several views; 70 5 designates the ash pit, 6 the floor and 7 the side wall. The main air inlet 8 and a plurality of auxiliary inlets 9 are provided below the grate bars 10, the main air supply or draft through the inlet 8 being from any external 75 source whereas the auxiliary air inlets 9 are adapted to permit the entrance of air from the gas producer lining subsequently to be referred to. The arch dome or cone top 11 is provided with fuel intakes 12, whereby the 80 fuel is fed in any well known manner into the interior of the gas producer. Between the sloping wall or partition 13 of the interior of the arch or equivalent and the outer wall portion 14 a manifold 15 is provided 85 which is in communication with an air intake 16 extending through the top of the dome and steam and water conduits 17, 17^a, which extend outwardly and through the outer wall 18 of the gas producer. 90

The producer gas outlet 20 is located near the top of the gas producer and below the dome 11 and leads to a superheater or other construction in the manufacturing plant, not shown.

Referring particularly to Figure 1 of the drawings, it will be observed that the walls of the ash pit are provided with enlarged openings 21, immediately below the gas producer lining, said openings, of course, com- 100

municating with the openings 9 whereby the air entering the gas producer lining either by natural draft or forced draft, cools the wall of the gas producer and is itself pre-heated.

- 5 The gas producer lining proper is composed of superimposed, segmental blocks such as shown by Figures 6 and 10 of the drawings. Specifically the outer block 22 and 10 the inner block 23 are segmental in shape and interfit so as to produce a circular gas producer lining, defining the gas producing chamber B, as clearly shown by Figure 2 of the drawings. The outer block 22 is of 15 special construction having a back wall 24 and a front wall 25, the superimposed blocks being set immediately adjacent the outside wall 18 of the producer as shown by Figures 1 and 2 of the drawings. The block is provided with vertical channels or passageways 27, 28, and top and bottom longitudinal channels or passageways 28^a, 29, which of course communicate with the vertical passageways 27, 28. The front wall or face 25 of the block 25 is also provided with top and bottom channels or air passageways 30, 31, which communicate with the vertical passageways above referred to and in turn with the longitudinal passageways when the 30 blocks are set on each other. In order to permit the respective outer blocks 22 to be set properly, the top of the front wall 25 is provided with a tongue 32 and the end wall 33 of the block is provided with a groove 34, 35 the opposite end wall of the block having a tongue 35. A groove 36 extending longitudinally of the bottom of the block permits it to interfit with the corresponding tongue 32 of the next adjacent block as the producer 40 lining is being built. In other words, the tongue 32 on the top of the front wall 25 and the tongue 35 on the end wall of the block interfits with corresponding grooves 36, 34, of the next adjacent block, it being of course understood that the channels or passageways 45 28^a, 29, are continuous and that the vertical passageways through the blocks are also continuous throughout the entire producer lining.
- 50 The inner block 23 of the producer lining or wall is similar in construction when the entire rear wall of the block 22 is regarded as cut away. In other words, blocks having three ribs 37, 38, 39, are formed with the 55 front wall or face 40, the said inner block being set so that the ribs 37, 38, 39, abut the faces 25 of the outer blocks, the passages or channels 30, 31, thus communicating with the vertical passages as well as the longitudinal top and bottom passages thus formed when the superimposed blocks 23 are thus set. In the same manner, the tongues 41, 42, of the inner or front block interfit with the 60 grooves 43, 44, on the end and bottom of the 65 respective inner blocks heretofore referred

to, when they are set. Particular attention is directed to the fact that the producer lining thus formed, which consists practically of a double wall of superimposed blocks permits of the maximum air circulation through 70 the interior or body of the lining, so that the air entering the manifold from the air intake and the steam or water as the case may be entering the manifold from the conduits 17, 17^a, may circulate in every direction through 75 the entire producer lining. The inner block 23 may be regarded as set in a staggered relation with respect to the outer block 22 but it will be readily recognized that the passages 30 and 31 of the outer block permit the 80 air to enter the passages between the respective ribs 37, 38, 39, as well as the top and bottom longitudinal passages formed between the inner and outer blocks since the said ribs 37, 38 and 39, are cut short of the 85 top and bottom of the block.

Under certain conditions a producer lining may be constructed of blocks such as shown by Figures 7 to 11 inclusive wherein the producer consists of an outer shell 45, an asbestos 90 lining 46 and a brick wall 47. Blocks of the single inner lining wall 23^a of Fig. 11, may be set so that the ribs 37, 38 and 39, abut the brick lining 47 so as to produce both longitudinal air passageways or channels and the 95 communicating air passageways or channels 48. In the construction particularly shown by Figure 1 of the drawings, it will be appreciated that a producer lining constructed in the manner shown and described will permit of the maximum of air circulation throughout its entire surface. In fact, the lining may be regarded as consisting of a triple wall and consequently heat radiation to the atmosphere is reduced to a minimum. 100 Under practical working conditions, it will be readily recognized that any portion of the gas producer lining may be easily replaced, if necessary, thus reducing the replacement cost, avoiding the necessity of tearing down 105 the entire gas producer as has been the practice in many instances heretofore, and minimizing the loss of time. Under the most trying conditions, the inner wall 23 may be 110 partially or entirely replaced without affecting the outer wall built up of the blocks 22. We have shown a gas producer constructed of segmental blocks and it will be readily recognized and appreciated that other 115 types of gas producers may be constructed and linings of refractory materials made embodying the above principle of wall construction.

From Figs. 1 and 2 it will be seen that the two communicating systems of horizontal and vertical passages, that is, the inner one and the outer one, are so spaced laterally of the wall structure that the portions of the refractory blocks defining such passages, i. e. the portions 24, 25 and 40, are progressively 120 125 130

thicker toward the inside of the wall, this arrangement being conducive to longer life for the refractories exposed to the fire, and to the economy of refractory material, as well as tending toward a more uniform utilization of heat as between the systems of passages, and, in consequence, a more uniform preheating of the air and steam flowing therethrough.

While we have illustrated and described our invention with some degree of particularity, we realize that in practice various alterations therein may be made. We therefore reserve the right and privilege of changing the form of the details of construction or otherwise altering the arrangement of the correlated parts without departing from the spirit of the invention or the scope of the appended claims.

Having thus described our invention, what we claim as new and desire to secure by United States Letters Patent is:—

1. In gas producer apparatus; a gas producer wall comprising superposed double courses of refractory blocks defining a gas producer generating chamber, each double course having a plurality of laterally spaced horizontally disposed passages with intercommunicating channels therebetween, and vertical passages through the courses connecting superjacent horizontal passages, together with air and steam inlets for the passages and a producer gas outlet for the chamber, the lateral spacing of the horizontal and vertical passages being such that the bodies of refractory material defining said passages are successively thicker toward the inner side of the wall.

2. In gas producer apparatus of the character described, a wall defining a gas producer chamber and formed of an inner layer and an outer layer, of refractory blocks, said outer layer having a system of intercommunicating horizontal and vertical passages therein, and said inner layer having a system of intercommunicating horizontal and vertical channels on its face adjacent the outer layer forming with said outer layer a similar system of passages, and air and steam inlets for the passages and a producer gas outlet for the chamber.

3. In gas producer apparatus of the character described, a wall defining a gas producer chamber and formed of an inner layer and an outer layer, of refractory blocks, said outer layer having a system of intercommunicating horizontal and vertical passages therein, and said inner layer having a system of intercommunicating horizontal and vertical channels on its face adjacent the outer layer forming with said outer layer a similar system of passages, together with transverse passages in the outer layer communicating with the two systems of vertical and horizontal passages, and air and steam inlets for

the passages and a producer gas outlet for the chamber.

In testimony whereof we affix our signatures.
